SAFETY RAZOR

Nicholas Testi, Boston, Mass., assignor to Gillette Safety Razor Company, Boston, Mass., a corporation of Delaware

Application July 7, 1944, Serial No. 543,767

3 Claims. (Cl. 30—65)

This invention relates to safety razors of the type having cooperating blade-clamping members between which thin replaceable blades are clamped and supported adjacent both of its cutting edges for shaving.

In one aspect, the invention consists in a so-called "one-piece" razor, that is to say, a razor to which a fresh blade may be supplied and from which a used blade may be removed without detaching any of the blade-clamping members. Such a razor has no loose parts that are likely to be dropped or mislaid. It is a one-piece razor in this sense, although made up of separate parts which are capable of being detached from time to time for special inspection or cleaning.

The improved razor of my invention is adapted and designed for use with open-end blades, that is to say blades having a central longitudinal slot opening through one of the unsharpened end edges of the blade. The razor includes the usual means by which the two blade-clamping members may be positively clamped together with a blade between them. It also includes a spring arranged to draw the blade-clamping members together with a limited yielding pressure when they are released from positive blade-clamping engagement. It is the action of this spring in permitting a yielding separation of the blade-clamping members to a limited extent that enables the user to introduce an open-end blade between the blade-clamping members against retarding pressure of the blade clamping members, and similarly to remove a used blade. By exerting a slight and entirely convenient amount of force, the user may readily cause the blade to separate the clamping members sufficiently to admit the blade, and in the same manner may overcome the yielding resistance to removal exerted by the blade-clamping members upon the blade.

These and other features of the invention will be best understood and appreciated from the following description of a preferred embodiment thereof, selected for purposes of illustration and shown in the accompanying drawings in which:

Fig. 1 is a view in perspective on an enlarged scale of the razor having its cap and guard members clamped with a blade in shaving condition between them;

Fig. 2 is a view of the razor in longitudinal section;

Figs. 3 and 4 are views of the razor head in cross-section showing it respectively in blade-receiving and blade-clamping condition; and

Fig. 5 is a view in perspective showing the cap

member from beneath and also indicating a blade (in dotted lines) being introduced beneath the cap.

The illustrated razor, in its general construction, is of the "Gillette" type in that it includes cooperating cap and guard members shaped to impart transverse curvature to a flexible blade presented between them and to clamp and support the blade in that condition for shaving. It will be understood, however, that the invention is not restricted to that or to any particular type of safety razor but with suitable modifications may be embodied in any safety razor employing replaceable blades.

15 The razor as herein shown is designed to employ a double-edged blade of the character shown in Fig. 5. This blade 10 is generally rectangular in outline and provided in each of its four corners with a reentrant notch. The notches at one end of the blade define an elongated unsharpened end and hinge portion 11. The blade is sharpened along both longitudinal edges and provided at its other end with an open elongated unsharpened end portion 12. The open end 12 of the blade is divided by a central longitudinal slot 13 and this slot is provided centrally with a circular enlargement or aperture 14 for the cap spindle and with intermediate enlargements 15 shaped to fit corresponding blade-locating projections of other razors in which the blade is adapted to be used.

20 The razor herein illustrated in certain details of its structure is adapted to accommodate the illustrated blade, and it will be understood that for handling blades of different outline corresponding changes in the construction of the razor may be made, all within the scope of the present invention.

25 The blade-supporting or guard member 16 of the razor presents an upper blade-engaging face of convex contour having outwardly and downwardly curved guard bars 17 disposed along both of its longitudinal edges. The body of the guard member is shaped to present parallel longitudinal fulcrum shoulders 18 over which the blade is flexed in shaving position. The guard member also has a central perforation 19 and is rigidly connected to a ferrule 20 permanently fitting at its lower end within the upper end of a sleeve or barrel 21 which forms the handle of the razor.

30 The cap member 22 is slightly narrower than the guard member. It is provided with a blade-engaging face concave in transverse curvature and has outer edges which are wider apart than the fulcrum shoulders 18 of the guard member.

It is provided with a central medial blade-locating rib 23 from which projects a spindle 24 threaded at its lower end. The spindle 24 fits freely within the ferrule 20 of the handle. The cap is entirely unobstructed at its ends and, in fact, is slightly beveled at each corner to facilitate the introduction of a blade beneath it.

In addition to the ferrule and the sleeve 21, the handle includes an elongated tubular nut 25 having a hollow stem that fits freely within the barrel 21 and is provided with an annular shoulder 26 at a point some distance above or within the knurled end of the nut 25. Above the shoulder 26 extends a sleeve portion 27 of reduced thickness which is internally threaded at its upper end to engage the lower threaded end of the cap spindle 24. A long annular chamber is thus formed between the inner wall of the barrel 21 and the outer wall of the reduced sleeve 27 of the tubular nut. A long compression spring 28 occupies this annular chamber, bearing at its upper end against the lower end of the ferrule 20 and at its lower end upon the shoulder 26 of the tubular nut. By its downward pressure the spring 28 tends at all times to depress the stem 24 threaded into the nut and to urge the cap member yieldingly toward the guard member. The pressure of the spring is such as to maintain the blade 10 yieldingly engaged between the two blade-clamping members 16 and 22 of the razor. Its length is such that when the stem 24 is released by a turn or a turn-and-a-half of the nut 25, the yielding pressure of the blade-clamping members on the interposed blade is just sufficient to retain the latter in whatever position it is left between them, and to permit it to be advanced or retracted against the yielding frictional pressure thus exerted upon it.

In practice, the blade 10 may be rigidly clamped for shaving, as shown in Figs. 2 and 4, by rotating the nut 25 in a clockwise direction to the limit of its movement and thus positively drawing down the cap 22. When it is desired to remove the blade, the nut 25 may be turned reversely for one to one-and-a-half turns. The threaded sleeve 27 is thus slightly lowered upon the threaded end of the spindle 24 and the length of the annular chamber between it and the barrel 21 correspondingly lengthened. The spring 28, however, prevents any substantial lifting of the cap 22 but maintains it yieldingly in practically the same position in which it was formerly retained positively by its threaded connection with the nut 25. Under these conditions the cap 22 is free to be lifted or the two blade-clamping members are free to be separated against the compression of the spring 28. This reduces the pressure upon the interposed blade to an extent permitting it to be yieldingly withdrawn by the user from between the two blade-clamping members. Similarly after cleaning and drying, the used blade or a fresh blade may be forcibly advanced between the two blade-clamping members displacing them sufficiently to permit the movement of the blade.

When a blade is inserted between the cap and guard members, its open end straddles the blade-locating rib 23 as suggested in Fig. 5 and

the two sharpened side portions of the blade pass on opposite sides of the rib until the advancing movement of the blade is arrested by the engagement of the inner end of the slot 13 with the left-hand end of the rib 23. The blade is thus gauged in its correct longitudinal position in the razor.

The blade may be presented by hand to the razor by the user or it may conveniently be delivered from a magazine of the character shown in my copending application Ser. No. 461,702, filed October 12, 1942, now Patent No. 2,359,807. That magazine is provided with flanges which engage the used blade in the razor when the magazine is brought into operative relation with the razor and initially displace the used blade. That blade is, accordingly, held under yielding pressure by the cap until the fresh blade is advanced from the magazine by operating its feed slide. The yielding pressure of the cap insures accurate registration of the advancing blade with the end of the blade it is to eject from the razor and replace.

Having thus disclosed my invention and described in detail an illustrative embodiment thereof, I claim as new and desire to secure by Letters Patent:

1. A safety razor having in combination, a guard of convex contour unobstructed at both ends, a tubular handle secured thereto, a cap of concave contour, a threaded stem attached thereto and telescopically received in said handle, a tubular nut rotatable in said handle and shouldered, thereby forming an annular chamber in the handle, a blade-locating projection disposed between the ends of the cap, and a spring in said chamber normally urging the cap and guard together with a yielding pressure permitting the insertion or withdrawal of an open-end blade, and threaded connection between the nut and the stem of the cap for drawing the cap positively into blade-clamping position without substantial displacement of the spring.

2. A safety razor having, in combination, a rigidly-connected handle and guard, a cap co-operating with the guard being unobstructed at both of its ends, a blade-locating rib immovably fixed to one of said co-operating members and located between the same, a spring associated with said handle normally urging the cap and guard together with a yielding pressure permitting the insertion or withdrawal of an open-end blade, the blade straddling said rib, and means for moving the cap and guard positively into blade-clamping relation.

3. A safety razor having, in combination, cap and guard members shaped to flex and support an open-end blade interposed between them and being unobstructed at both ends, a blade-locating rib immovably fixed to one of said members and disposed between the same, a spring acting at all times to urge said members together yet permitting the blade to be inserted against yielding pressure between them to straddle the rib, and screw-threaded means operating to move the cap positively into blade-clamping position.

NICHOLAS TESTI.
